CONTAINER

Reginald W. Manning, Phoenix, Ariz.

Application October 3, 1933, Serial No. 691,943

3 Claims. (Cl. 2—173)

This invention relates to containers such as paper sacks, cardboard cartons, and the like used for packing food stuffs and other similar commodities, and has for its objects, the provision of a container having an image or figure imprinted thereon so that the container may be used as a toy; said figures giving the container a distinctive appearance and aiding in the identification of it and its contents. Other objects 10 will appear hereinafter.

I accomplish these objects by means of the devices and manufactures illustrated in the accompanying drawing, in which—

Figure 1 is a perspective view of one form 15 of my invention. In this case a sack container is shown inverted and adapted to be used as a toy mask.

Figure 2 is a similar view of a modified form, being in this instance, a carton adapted to be used as either a mask or a jack-o'-lantern.

Figure 3 is another modified form wherein the figure is imprinted on the container so that it may be used as a toy.

Figure 4 is an alternative form of Figure 3 25 wherein the figure imprinted on a portion of the container adapts it for use as a toy doll.

Similar numerals refer to similar parts in all views.

In each of the forms illustrated the numeral 30 2 designates the container body. On this body is imprinted an image or figure, 3. This figure is usually the head of some animate object such as a human being, or animal. However, the image may be quite grotesque and represent an ogre, a caricature, or even an inanimate object, 35 such as a skull.

In the form shown in Figure 1 the container, which is an ordinary foldable paper sack, has the image imprinted thereon so that when the 40 sack is inverted it may be slipped over the head of the wearer and used as a mask. Eye holes 11 are imprinted on the portion of the sack below the figure 3 so they may be readily pierced, and reinforced holes 14 provided so that strings 45 may be inserted to hold the mask in place by running them under the armpits of the wearer.

The form shown in Figure 2 shows the adaptation of the invention to a cardboard carton. As illustrated, the carton is inverted, one side (the back, in this instance) may be partially broken out as indicated by the broken lines 5, and strings 6 employed to hold the device on as a mask. Otherwise a lamp 7 may be inserted in the device and the same used as a jack-o'-lantern. The realism of the figure in this form is enhanced by having the lines 8 of the nose and mouth and eyes scored to break when pressed. The upper part of the mouth may then be raised and pasted in place, thus causing the nose 9 to 55 protrude. The eye openings may likewise be

broken out and an inner container of colored paper used to diffuse and color the light emitted thru the mouth, eye and nose openings of the figure.

In Figure 3, the cylindrical cardboard carton body 2 is inverted and the figure of the head of a horse imprinted thereon. A broom handle 12 may then be inserted from the back of the carton and it may then be used as a hobby-horse.

Figure 4 illustrates an oblong cardboard carton of smaller dimensions. The figure 3 is imprinted on a portion of one end only.

This enables the carton to be used as a doll when the paper dress 15 is attached as illustrated.

It is to be understood that in all forms only a portion of the surface of the container, whether it be sack, bag, or carton, is imprinted with the images and figures herein illustrated. The 20 remaining portion of the surface is left blank as indicated at 16, Figure 3, or may be imprinted with figures, writing and the like to designate the contents of the container, its use, or for trademarks, advertising, etc.

It is obvious that my invention, as herein described and illustrated, is subject to various modifications and changes. Therefore, I wish to be limited only by the following claims.

I claim:

1. A container of pliant material having the caricature of a face imprinted mainly on one side with the details thereof extending around the adjacent sides and having the outlines of the features scored to break when pressed, whereby the outlines thereof may be accurately broken out.

2. A container of pliant material having the caricature of a face imprinted mainly on one side with the details thereof extending around the adjacent sides and having the outlines of the features scored to break when pressed, whereby the outlines thereof may be accurately broken out, said imprinted face being positioned with the top toward the closed end so that when 45 the container is open and inverted it may be used as a mask.

3. A rectangular tubular container of pliant material having one end closed to form a bottom therefor, and having the image of a mask face 50 imprinted on one side thereof with the top of said image toward the closed bottom of said container, the details of said mask face extending around the sides of and over the bottom end of said container, and having outlines of the 55 eyes, nose, and mouth of said image scored into the material of said container to break when pressed so that openings can easily be made for said features conformable to said printed image.
